Patented Feb. 10, 1925.

UNITED STATES PATENT OFFICE.

MARTIN T. GRAF, OF BUFFALO, NEW YORK.

KNIFE SHARPENER.

Application filed April 15, 1924. Serial No. 706,702.

To all whom it may concern:

Be it known that I, MARTIN T. GRAF, a citizen of the United States, residing at Buffalo, in the county of Erie and State of New York, have invented a new and useful Improvement in Knife Sharpeners, of which the following is a specification.

This invention relates to a knife sharpener having a pair of sharpening disks and has for its object the production of a sharpener of this character which is simple in construction, which will not chatter while in use, which permits of reliably holding the disks against movement in case the same are not perfectly flat, which permits of readily centering and assembling the disks on the bracket, and in which the disks are so constructed that the same are not brittle and liable to crack or break.

20 In the accompanying drawings:—

Figure 1 is a perspective view of my improved knife sharpener, showing the same in use. Figure 2 is a side elevation thereof, on an enlarged scale. Figure 3 is a 25 transverse section of the same taken on line 3—3, Fig. 2. Figure 4 is a plan view of the sharpener detached from its support. Figure 5 is a vertical longitudinal section taken on the correspondingly numbered line 30 in Figure 4.

Similar characters of reference indicate like parts throughout the several views.

In its general organization this knife sharpener comprises a bracket 10 and two 35 sharpening disks 11 mounted edge to edge on the bracket so that upon drawing a knife 12 with its edge through the notch formed between the opposing edge portions of the disks the knife edge will be sharpened. 40 This bracket in its preferred form has a base 13 which may be secured by screws 14 or otherwise to a support 15 of any suitable character, such for instance as a board, a table top, wall or the like. Projecting upwardly from the rear end of this base is a standard 16 which inclines rearwardly and is provided on its front side with a rearwardly inclined flat face 17 upon which the rear flat sides of the sharpening disks rest 45 in a rearwardly inclined position with their peripheral edge portions engaging or nearly engaging each other. The disks are detachably connected with the standard so as to be removable thereon, also adjusted toward 50 each other, also rotated to bring different parts of their peripheries to the working

position and also permit of reversing the disks so as to enable both peripheral corners of each disk to be used and thus prolong the utility of the sharpener. The fastening 60 means for this purpose preferably comprise washers 18 engaging with the front flat sides of the sharpening disks and fastening screws each passing through openings 19, 20 in each companion washer and disk and engaging the threaded rear end of its shank 21 with a correspondingly threaded opening in the standard while its head 22 bears against the front side of the respective washer. The opening in each disk is somewhat larger in diameter than the screw shank passing through the same in order to permit the disks to be readily moved laterally with reference to the fastening screws 70 for bringing the peripheries of these disks 75 into the desired working position.

It has been found in practice that when the standard is made comparatively thin at its lower end that the bracket is liable to vibrate or chatter upon drawing a knife between the disks and thus produce an unpleasant feeling and disagreeable noise. This is obviated by providing the standard 80 with a rear inclined side 23 which is more nearly vertical than the front side of the 85 standard, whereby the front and rear sides of the same converge upwardly and produce a standard having greater thickness at its lower end which rests on the base than the upper part thereof which carries the sharp- 90 ening disks.

When the disks are manufactured the same are liable to be warped somewhat during the tempering operation and when thus distorted it is difficult to clamp the same in 95 place between the washers and the standard of the bracket and prevent the same from turning owing to the reduced contact between the disks and the standard. To overcome this difficulty the standard is provided 100 on its face with recesses 24 opposite the central parts of the disks so that only the marginal parts of the disks engage with the standard, and as these marginal parts present the maximum surface area and 105 are also farthest from the axes of the disks it is possible to hold the latter against turning by the pressure of the screws and thus ensure satisfactory operation of the sharpener.

Sharpening disks, when tempered so that they are of the same degree of hardness

throughout and present sharp cutting corners thereon, are liable to break when in use or when clamped on the bracket. To overcome this the disks in the present case are so tempered or treated that only the peripheral portions of the same are hardened while the central parts thereof are made relatively soft. It follows from this that when fastening the disks to the standard and when drawing a knife between the same for sharpening purposes the soft center of the disks will give sufficiently to prevent breakage while the hard periphery of the same will maintain hard corners and operate effectively to sharpen a knife drawn past the same.

For the purpose of permitting the disks to be easily, quickly and conveniently assembled with the standard the front side of the latter is provided at the lower end of the front face with a horizontal transverse edge, shelf, rib or shoulder 25 upon which the lower edge portions of the disks are adapted to rest, and the standard is also provided on opposite sides of its front face with forwardly projecting retaining lugs 26 which are adapted to engage with the opposite outer edges of the disks. The distance between the lugs is preferably equal to the combined diameter of the disks. Upon therefore simply depositing the two disks upon the shelf between the two retaining lugs the disks center themselves automatically by gravity inasmuch as the same occupy practically the entire space between the lugs above the shelf and as the front face of the standard inclines backwardly there is no tendency for the disks to fall off from the standard after being deposited thereon, thereby avoiding displacement of the disks and permitting of readily fastening the same by means of screws to the standard.

In assembling the disks it is preferable to first clamp one disk in place while the same is in engagement with one of the retaining lugs and then fasten the other disk by turning the fastening screw in the direction which will tend to move the last mentioned disk toward the one which was first tightened, thereby ensuring fastening the disks in place so that their opposing

edge portions engage with each other and form a good sharpening notch between them.

By arranging the standard in an inclined position this serves to always ensure drawing the knife in the proper direction between the disks and it also permits of operating the sharpener in the most effective and convenient manner. By inclining the standard 16 backwardly or in the direction in which the knife is drawn while its edge is in engagement with the sharpening disk, this avoids the possibility of engaging the knife improperly with these disks and instead ensures engaging the knife edge with the upper front edges of the disks at the proper angle in which the disks operate most effectively for sharpening the knife and also enabling the operator to hold the knife in the most natural position while doing this work.

I claim as my invention:

1. A knife sharpener comprising a bracket having a base, a standard rising from said base, a pair of parallel screw threaded openings and recesses arranged on the rear side of a standard, one around each threaded opening, sharpening disks engaging with the rear side of said standard and each arranged with its central part over one of said threaded openings and the respective recess, and fastening screws passing through said disks and recesses and engaging said threaded openings.

2. A knife sharpener comprising a bracket having a base, a standard rising from said base and having an upwardly facing inclined rear side, a horizontal shelf arranged transversely on the lower part of said rear side and upright retaining lugs arranged on said rear side at opposite ends of said shelf, a pair of sharpening disks resting with their corresponding flat sides against said rear side of the standard and each disk engaging the lower part of its periphery against said shelf and the outer part of its periphery against the inner side of one of said retaining lugs, and fastening screws connecting said disks with said standard.

In testimony whereof I affix my signature.

MARTIN T. GRAF.
